UNITED STATES PATENT OFFICE.

ANTAL TELEKY, OF NEW YORK, N. Y.

LIFE-PRESERVING GARMENT.

1,096,574.

Specification of Letters Patent. Patented May 12, 1914.

Application filed November 1, 1912. Serial No. 729,049.

To all whom it may concern:

Be it known that I, ANTAL TELEKY, a subject of the King of Hungary, and resident of the city of New York, in the county of New York and State of New York, have invented certain new and useful Improvements in Life-Preserving Garments, of which the following is a specification.

The present invention relates to a life preserving or life saving garment, and has for one of its objects to provide a water-tight garment of this type which can be conveniently applied to the body and worn in case of a marine disaster or accident.

Another object of the invention is to produce a garment with means, whereby the wearer will be kept afloat in an upright position in the water.

A further object of the invention is to provide a garment with means which facilitates in an effective manner the motion of the body through the water by the movement of the hands and arms.

With these and other objects in view, which will more fully appear as the nature of the invention is better understood, the same consists in the combination, arrangement and construction of parts hereinafter fully described, pointed out in the appended claim and illustrated in the accompanying drawings, it being understood that many changes may be made in the size and proportion of the several parts and minor details of construction within the scope of the appended claim without departing from the spirit or sacrificing any of the advantages of the invention.

One of the many possible embodiments of the invention is illustrated in the accompanying drawings, in which:

Figure 1 is a perspective view of a garment constructed in accordance with the present invention in an open position; Fig. 2 is a similar view of a portion of the garment in a closed position; and Fig. 3 is a front elevation of the hand covering portion of the garment on an enlarged scale.

The garment is made of a water-proof or impervious material of any suitable type, its seams and joints being made water-proof.

Generally speaking, the invention consists of a union garment, to the neck portion of which is attached a head covering, and the sleeve and leg portions of which are provided with hand and feet coverings, respectively; the hand coverings being provided

with means for facilitating the motion of the wearer through the water.

In the drawings, the numeral 10 indicates the trunk portion of the garment, provided in its front with a closure slit 11 extending from the neck portion 12 to the belt or waist portion 13 thereof. The edges of the closure slit are provided with impervious overlapping strips 14 and 15, to which are attached coacting separable fastening means 16 and 17, which are shown in the drawings to be of the head and socket fastener type, although it will be easily seen that any other suitable means may be used just as well. The trunk portion 10 is provided with sleeves 18, with which are made integral hand coverings 19 in the form of gloves. The finger and thumb portions of these gloves are united by webs 20 for a purpose hereinafter to be described.

With the trunk portion of the garment are made integral leg portions 21, the free ends of which are provided with feet coverings 22, to the sole portions of which are secured weights 23 of any suitable size, which tend to hold the body in an upright position when floating in the water.

To the shoulder portion of the garment is attached a head covering 24, preferably a hood, inclosing entirely the head of the person, but leaving a small portion of the face exposed. The hood 24 has a downwardly extending flap 25, to the free edges of which are attached coacting fastening means 26 and 27, for instance of the head and socket fastener type.

Above the waist portion of the garment is arranged a life preserver belt 28 of the well known construction. This belt is fastened to the garment, and held in proper position upon the body of the person by straps 29 adapted to be engaged by buckles 30, said buckles and straps being secured in any suitable manner to the ends of the life preserver belt.

These garments are usually made large enough to accommodate any person of the ordinary size; and to hold the same properly in position upon the body, a belt 31 is attached to the waist portion thereof. One of the free ends of the said belt is provided with a buckle 32, adapted to coact with a plurality of perforations 33 in the other end thereof. A ring 34 is held upon the belt, and serves for the attachment of a line or cord.

The garments are stored away with their closure slits 11 open, and the ends of the life preserver belt 28 and the waist belt 31 disengaged from each other. The person can 5 thus easily step into the closure opening, place the arms into the sleeves and draw up the garment so that the legs will enter the leg portions 21, 21. After this, the belt 31 is drawn tight around the waist line, where- 10 by the garment will be held in the proper position upon the body. The closure slit 11 is then closed, by which operation the neck portion 12 will be drawn tightly around the neck of the wearer. The straps 29 are then 15 brought into engagement with their corresponding buckles 30, and finally the hood 24 drawn over the head, the fastening devices upon the flap 25 engaged with each other, whereby a water-tight covering is provided 20 for the body, which will permit the body to stay in the water for a considerable time without exposure to cold. It is to be ob- 25 served that the body will float in an upright position by reason of the weights 23 upon the sole portions of the feet coverings of the garment. The webs 20 connecting the finger and thumb portions of the hand coverings serve the same purpose as those between the digits of aquatic birds, that is to say they

are intended to aid the motion of the float- 30 ing body through the water by the movement of the arms and hands.

What I claim is:—

A life saving garment comprising a trunk portion provided with sleeves and legs, said 35 trunk portion being provided with a closure slit, impervious overlapping strips upon the edges of said slit, detachable fastening devices arranged upon both of said strips, foot coverings upon the free ends of said legs, 40 balancing weights attached to the sole portions of said foot coverings, hand coverings in the form of gloves upon said sleeves, webs connecting the fingers and thumb portions of said hand coverings, a safety belt at 45 attached above the waist line to said trunk portion, and a hood permanently attached to the shoulder part of said trunk portion, said hood having a downwardly extending flap and coacting fastening means on the 50 free edges of said flap.

Signed at New York, in the county of New York and State of New York, this 30th day of October, A. D. 1912.

ANTAL TELEKY.
